(57) **CLAIM**

The ornamental design for an elevator control panel as shown and described.

DESCRIPTION

FIG. 1 is a perspective view of an elevator control panel showing our new design;

FIG. 2 is a front view thereof;

FIG. 3 is a back view thereof;

FIG. 4 is a side view thereof;

FIG. 5 is another side view thereof;

FIG. 6 is a top view thereof;

FIG. 7 is a bottom view thereof; and,

FIG. 8 is a perspective view as shown in a configuration of use.

The broken lines in the drawings depict portions of an elevator control panel that form no part of the claimed design. The broken lines depicted in FIG. 8 are shown with symbolic breaks that surround the perimeter. Any portion of the design beyond the symbolic breaks forms no part of the claimed design.
